ERNEST BUCHHOLTZ, OF WEALDSTONE, HARROW, ENGLAND, ASSIGNOR TO THE OIL-FLAME FURNACE COMPANY, LIMITED, OF HIGH HOLBORN, ENGLAND.

LIQUID-FUEL BURNER AND FURNACE.

1,114,729.

Specification of Letters Patent.

Patented Oct. 27, 1914.

Application filed April 10, 1913. Serial No. 760,158.

To all whom it may concern:

Be it known that I, ERNEST BUCHHOLTZ, a subject of the German Emperor, and resident of "Penlan," Marlborough Hill, Wealdstone, Harrow, in the county of Middlesex, England, have invented new and useful Improvements in Liquid-Fuel Burners and Furnaces, of which the following is a specification.

10 This invention relates to improvements in liquid fuel burners and furnaces for ore smelting and other purposes, of the kind in which the fuel to be vaporized and consumed is contained in a tray or shallow open vessel, 15 or in a number of such trays or vessels superposed, and with an air admission space between neighboring vessels. Such a vessel or vessels is or are usually arranged in an opening or passage communicating with a 20 combustion chamber or flue, so that the air passing through the opening or passage picks up or carries hydrocarbon vapors and particles from the vessel or vessels and subsequently supports, or assists in supporting 25 the combustion of the hydrocarbon.

Burners of this type are advantageously employed for consuming crude oils, petroleum refuse, gas oil, shale oil, tar oil, blast furnace oil and so on. The trays or vessels, 30 if desired may be arranged in water baths in order to prevent overheating of the trays and to supply steam or water vapor which intermingles with the fuel vapors and air.

Now according to the present invention 35 the burner of the type referred to is arranged in a passage or aperture opening into the interior of a chamber, which may be called the primary combustion chamber, upon the rear wall of which there is formed 40 a nose or bridge extending forwardly in the direction of the burner. For example, the nose may extend over a third of the distance separating the rear wall from the front wall, and the upper surface of the nose or bridge, 45 may be concave while the under surface may be horizontal, these two surfaces merging into a rounded edge portion. Openings or 50 passages for the exit of the mixed vapors, air, and if desired steam or water vapor, from said chamber into the secondary or 55 final combustion chamber or flue, are formed beneath the nose or bridge and such openings may be contracted in the direction of the combustion chamber. These openings are hereinafter termed nozzles. There may

be several rows of such nozzles, which are preferably arranged in a staggered fashion. The nose or bridge is conveniently arranged at a distance above the bottom of the primary combustion chamber equal to about one 60 third of the height of that chamber, the height being for example a little less than three times the distance separating the front and rear walls of the primary combustion chamber. The under surface of the nose or 65 bridge is suitably at a slightly higher level than that at which the surface of the liquid in the lowest tray of a series is situated.

In the accompanying drawings:—Figure 1 is a vertical section through the line C—D 70 of Figs. 2 and 3, of the primary combustion chamber, and showing the detachable liquid fuel burner arrangement. Fig. 2 is a front elevation of Fig. 1. Fig. 3 is a vertical section through the line A—B of Fig. 1 showing the openings for the passage of the burning oil gases from the primary combustion chamber into the furnace space or smelting chamber and Fig. 4 is an enlarged detail sectional view of a water bath and oil tray 75 arrangement fitted with an air regulator on the front side of the water tray to regulate the air space between the trays.

Referring to the drawings *a* indicates a gas mixing and primary or partial combustion chamber having an inner layer or lining *b* of ganister, fire clay or fire brick, or any other suitable refractory material, and an outer shell or casing *c* of iron and the width and height of the interior of the chamber 80 may conveniently be in the proportion of about one to three. The chamber *a*, the roof and floor of which are preferably curved or semi-cylindrical, has an opening or passage-way *d* formed in its front side, which is 85 adapted to accommodate any suitable burner of the kind referred to, but particularly the arrangement comprising burner trays *e* and water trays *e'*. At the aperture or opening *d*, the iron casing may be formed as a horizontal tube *f*, and preferably, as shown at *g*, with a flared end for assisting the induction of air. An extra air inlet may be provided, in the form of a downwardly inclined passage *h*, situated just above the opening *d*, 90 and leading into the chamber *a*; the entrance to the passage *h* being preferably controlled by a valve of the hit-and-miss type, constructed of a plate *i*, having openings *j* formed therein, the said plate being adapted 95 100 105 110

to slide over openings j' formed in the iron casing c .

Upon the rear wall of the chamber a is formed a nose or bridge k extending forwardly in the direction of the trays. This nose or bridge k may extend over a third of the distance separating the rear wall from the front wall, and its upper surface may be concave as shown while the under surface, which is preferably at a slightly higher level than the surface of the liquid in the lowest burner tray, may be horizontal, the two surfaces merging into a rounded edge portion. The nose k is also preferably arranged at a distance above the bottom of the chamber a equal to about one third the height of that chamber. Below the nose or bridge k are formed openings or nozzles l leading from the chamber a to the secondary or final combustion chamber m , these nozzles being for the exit of the mixed vapor and air or other combustible mixture from the chamber a . These nozzles l may also, as shown, be contracted in the direction of the chamber m . There may be several rows of such nozzles, which are preferably arranged in staggered fashion as shown in Fig. 3.

The chamber a may be attached to the combustion chamber m by means of a frame a' or in any other desired or suitable manner. The front wall of the furnace or flue m has a comparatively thick lining o of fire-brick or refractory material, the lower part of which may be made considerably thicker as shown in Fig. 1, and in this thickened portion a tunnel p may be formed opposite the nozzles l . In addition to the regulation of the supplementary air supply provided by the hit and miss valve controlling the passage h , the primary air supply may be regulated, as shown in detail Fig. 4, by plates q of wrought iron or steel, which are adjustable upon the front sides of the water trays e' , by means of screws r , which pass through slots r' in the plates. The latter project below the lowest points of the trays e' , and by unfastening the screws r , the sheet q may be raised or lowered at will, 50 and so enlarge or diminish the distance between the lower edge of the tray to which it is attached and the oil surface of the tray e below it, so that in this way the inrush of the air into the chamber a through the spaces between the trays e' , can be regulated to produce the desired effect.

In operation, combustion begins at the surface of the fuel in the open vessels e and the natural draft causes air to enter by 60 the tubular inlet f of the chamber a and, in passing over the open vessels e to take up the burning vapors of such fuel, the latter having been vaporized partly owing to the heat in the walls or lining b of the chamber a . The air laden with these vapors and

also, if desired, bearing steam or water vapors due to evaporation of water in the trays e' , crosses the chamber a where combustion is continued and strikes the opposite wall thereof being deflected upwardly owing to the curvature of the upper surface of the bridge or nose k so that a certain amount of swirling motion is thus given to the mixed vapors and air and an intimate and uniform admixture thereof takes place. The mixture having undergone a more or less partial combustion is continuously delivered near the bottom of the chamber a to the chamber m through the nozzles l , the lower horizontal surface of the bridge or nose k 70 acting as a baffling surface and insuring the delivery of the mixture through the nozzles l . The heat absorbed and retained by the lining b of the chamber a effects an efficient pre-heating of the combustible mixture, and the combustion is completed within the chamber m . 75

What I claim is:—

1. A liquid fuel burner arrangement comprising a chamber having an opening in its front wall and delivery nozzles in its rear wall, an open fuel container arranged in the opening of the front wall and a nose or bridge upon the said rear wall said nose projecting above said delivery nozzles and 90 toward said container, substantially as set forth.

2. A liquid fuel burner comprising a chamber the height of which is greater than the distance between the front and rear walls and having an opening in the front wall and delivery nozzles in the rear wall, open liquid fuel containers arranged in the opening in the front wall, and a nose or bridge on said rear wall, said nose or bridge 100 having a flat lower surface and a concaved upper surface substantially as set forth.

3. A liquid fuel burner arrangement comprising a chamber, the height of which is greater than the distance from the front to the rear wall and having an opening in the front wall, and delivery nozzles in the rear wall, said front and rear walls being joined by a curved roof and curved floor, open fuel containing vessels superposedly arranged in the opening in the front wall, and a nose or bridge on the rear wall immediately above said delivery nozzles, said nose or bridge having a concaved upper surface 115 substantially as set forth.

4. A liquid fuel burner arrangement comprising a chamber the front and rear walls of which are separated by a smaller distance than that which separates the roof and floor and having an air intake opening 125 in its front wall and delivery nozzles in its rear wall, open liquid fuel containers arranged in the said air intake opening, a deflecting surface on the rear wall opposite said containers, and a baffling surface on 130

- said rear wall immediately above said nozzles substantially as set forth.
5. A liquid fuel burner arrangement comprising a swirling chamber having an air intake opening in its front wall and delivery nozzles in its rear wall, superposed open liquid fuel containers in said intake opening, a deflecting surface on the rear wall of said chamber, and a baffling surface on the 10 said rear wall immediately above said delivery nozzles and at a slightly higher level than the level of liquid in the lowermost container substantially as set forth.
6. A liquid fuel burner arrangement comprising a swirling chamber having an air intake opening in its front wall and delivery nozzles in its rear wall, a flared air intake tube arranged over the opening in the front wall, superposed open liquid fuel 15 containers arranged in said opening, and a nose or bridge on said rear wall projecting toward said front wall and arranged immediately above said delivery nozzles substantially as set forth.
- 20 7. A liquid fuel burner arrangement comprising a swirling chamber having a large opening and a passage in its front wall and delivery nozzles in its rear wall, superposed open liquid fuel containers arranged in the 25 opening of the front wall, an adjustable inlet valve arranged over the entrance to the passage through said front wall, and a nose or bridge on said rear wall immediately 30 above said delivery nozzles substantially as set forth.
8. A liquid fuel burner arrangement comprising a swirling chamber of greater height than length and having an opening in its front wall and delivery nozzles in its rear 35 wall, said delivery nozzles being nearer to the floor than to the roof of said chamber,

and a bridge or nose on said rear wall comprising a concave upper deflecting surface for the entering current of combustible mixture and a lower baffling surface immediately above said delivery nozzles substantially as set forth. 45

9. A liquid fuel burner arrangement comprising a swirling chamber the height of which is great compared with the distance 50 separating the front and rear walls, the front wall being formed with a large opening and with a passage above said opening adapted to direct a current of air downwardly into said chamber and the rear wall 55 of said chamber being formed with delivery nozzles situated near to the bottom of said chamber, superposed open liquid fuel containers in the opening in the front wall of said chamber, and a bridge or nose on the 60 rear wall of said chamber comprising an upper concaved deflecting surface and a lower flat baffling surface immediately above said delivery nozzles substantially as set forth. 65

10. A liquid fuel burner arrangement comprising a swirling chamber having an air intake opening in its front wall and delivery nozzles in its rear wall, an air intake passage arranged over said opening in 70 the front wall, superposed over liquid fuel containers arranged in said opening and spaced apart to form air passages, a nose or bridge on said rear wall and arranged above said delivery nozzles, and adjustable shutters 75 mounted on said containers and adapted for regulating the air passages between said containers substantially as set forth.
